CLAIM

The ornamental design for a brush stand for cleaning brushes, as shown, and described.

DESCRIPTION

FIG. 1 is a perspective view of the brush stand for cleaning brushes;

FIG. 2 is a front view of the brush stand for cleaning brushes;

FIG. 3 is a rear view of the brush stand for cleaning brushes;

FIG. 4 is a left side view of the brush stand for cleaning brushes (with the right side a mirror image thereof);

FIG. 5 is a top view of the brush stand for cleaning brushes;

FIG. 6 is a bottom view of the brush stand for cleaning brushes;

FIG. 7 is a perspective view of the brush stand for cleaning brushes in a horizontal brush storage use environment; and, FIG. 8 is a perspective view of the brush stand for cleaning brushes in a vertical brush storage use environment.

The broken lines depict environment and form no part of the claimed design.
